(57) CLAIM

The ornamental design for a sex toy, substantially as shown and described.

DESCRIPTION

FIG. 1 is a top, front perspective view of the sex toy; the view showing my new design;

FIG. 2 is a top, rear perspective view thereof;

FIG. 3 is a bottom, front perspective view thereof;

FIG. 4 is a bottom, rear perspective thereof;

FIG. 5 is a top view thereof;

FIG. 6 is a bottom view thereof;

FIG. 7 is a front view thereof;

FIG. 8 is a back view thereof;

FIG. 9 is a side view thereof; and,

FIG. 10 is another side view thereof.

The broken lines shown in the figures are for the purpose of illustrating portions of the sex toy, which form no part of the claimed design.
